UNITED STATES PATENT OFFICE.

JAMES EMERSON, OF WILLIMANSETT, MASSACHUSETTS.

STEAM-HEATING APPARATUS FOR RAILWAY-CARS.

SPECIFICATION forming part of Letters Patent No. 314,006, dated March 17, 1885.

Application filed April 24, 1884. (No model.)

To all whom it may concern:

Be it known that I, JAMES EMERSON, a citizen of the United States, residing at Willimansett, in the county of Hampden and State 5 of Massachusetts, have invented new and useful Improvements in Steam-Heating Apparatus for Railway-Cars, of which the following is a specification.

This invention relates to improvements in 10 devices for warming railway-cars by steam taken from the locomotive of the train, combined with auxiliary means for warming connected with the car and with said devices, the object being to provide greater protection and 15 safety for railway-travelers against being burned with the car in case of accident to the train, by removing all stoves and live fires therefrom while the train is in motion.

In the drawings forming part of this specification, Figure 1 is a plan view of the floor 20 of a railway-car, showing the sides and ends in section, having applied thereto a circulating system of steam-pipes and warming devices constructed according to my invention. 25 Fig. 2 illustrates the above-named circulating system of steam-pipes and warming devices separate from the car. Fig. 3 is a detail view.

In the drawings, D is the floor of the car; E, the sides, and w the platforms thereof.

30 A piece of flexible hose—such as is ordinarily used for making pipe-connections between cars—is indicated by a, and by means of said hose and the requisite intermediate pipe-connections between it and the locomotive steam 35 is taken from the latter and introduced into the pipe a', which runs under the platform w, and thence upward into the car, entering one side of the door m', running to the corner of the car, and connecting with the main 40 ducting-pipe b, which is properly covered to prevent the radiation of heat, and inclosed in a box, J, built in the corner formed by the junction of the side E and floor D of the car, as shown in Fig. 3. The conducting-pipe b 45 runs from end to end of the car, each end thereof being provided with suitable connections for taking or delivering steam, since either end of the car may be nearer the locomotive. The pipes a' are provided with stop- 50 valves 2 and 3, whereby more or less steam is allowed to enter pipe b or escape therefrom.

The steam-circulating system of pipes and coils, which is connected directly with pipe b for warming the car, is indicated by c. These pipes run along the side of the car above 55 pipe b, and coils are arranged in a position to be under the car-seats, in the ordinary manner. In the drawings the pipe and coils c are shown connected with the pipe b at one end by a branch, z, having a stop-valve, 6, therein. 60 A stop-valve, 4, is placed in pipe c between valve 6 and the coils and pipes beyond valve 4. At the other end of the car the pipe c is connected directly with the pipe b, a stop-valve, 5, being placed in pipe c near the latter. The 65 above-described slight difference in the manner of connecting pipes b and c at the two ends of the car occurs by reason of the additional pipe-connection e, which carries steam over the car-door m' to the pipes c' on the opposite side of the car. The two sections of pipes c'—one each side of the door m' in Fig. 1—are about on lines x x, Fig. 2.

A drip-pipe, d, in which is a valve, d', leads from one of coils c under the floor of the car 75 and enters boiler A, its end within the latter reaching nearly to the bottom thereof, as shown by dotted lines in Fig. 2. The pipe d conducts the hot water of condensation from pipes c to the boiler. The aforesaid pipe e is connected 80 with pipe c on one side of the car, and with the pipes c' and i on the opposite side. A stop-valve, g, is placed in pipe i at its junction with the pipe e and near the connection of the latter with the pipe and coils c'. The pipe and 85 coils c' extend from their junction with pipe e at one end of the car to the extreme end of the pipe h near the opposite end, and the coils c' are, like coils c, arranged to come under the 90 seats of the car.

A boiler, A, is suspended under the car-floor, and is provided with a heating device, B, shown in the drawings in the form of a circular lamp provided with suitable wick-tubes; but said heating device may consist of any 95 other suitable means for quickly lighting and extinguishing the fire, and for sufficiently heating water in boiler A to convert it into steam.

The pipe h, to the end of which the pipe c' is connected, is a drip or return pipe, whose 100 function is to conduct water which is the result of condensation in the pipes and coils c'

into the boiler A. To this end the pipe *h* passes through the head of boiler A and extends nearly to the bottom of the boiler, as shown in Fig. 2, that its lower end may be 5 continually submerged in the water.

A reservoir, K, is attached to the end of the vertical portion of pipe *h*, and a valve, 13, is placed between the latter and the reservoir. Water contained in said reservoir may be let 10 into the boiler through pipe *h* in case the latter requires water. Boiler A has an overflow-cock, 7, in its side, through which water is allowed to escape while pipe *h* is conducting water into the boiler to keep the water at the 15 height of said cock. A drain-cock, 8, is placed near the bottom of the boiler, through which all or a part of the water may be drawn therefrom.

The pipe *i*, which is connected to the head 20 of boiler A, is a live-steam-conducting pipe connecting the boiler A with the pipes and coils *c* and with the pipe *e*, and by means of the latter with the pipes and coils *c* on the opposite side of the car, if desired.

25 In practice the pipes *h* and *i* are boxed in the corner of the car in the manner described relative to pipe *b*.

The operation of my improvements is as follows: Steam is taken from the locomotive, and 30 through the connections *a* between the cars is conducted through the pipe *a'* to the main conducting-line *b*, and through the latter and said intermediate connections to all the cars of a train. Thus the pipes *b* of the cars constitute 35 a steam-supply main running through the same, within which a certain pressure is maintained, sufficient to force an adequate supply of steam therefrom into the heating pipes and coils of the cars with which said main is connected. The water of condensation which may collect in said supply-main is let out of it by opening valves 5 and *d'* and letting it pass through pipe *d* to the boiler, thus keeping the latter filled with hot water 40 ready for any emergency in which the car requires to be kept warm independent of the steam-supply from the locomotive. In warming the pipes and coils *c*, which are connected with pipe *b*, valve 2 being open, valves 5 and 45 4 are opened, letting steam flow into said pipes and coils, and any water of condensation in said pipes escapes through the pipe *d* to the boiler by opening valve *d'*. In very cold weather, when it is desirable to warm a car quickly or 50 55 to maintain more heat in the car, and condensation takes place rapidly, the car can be more quickly heated by closing valve 4 and opening valve 6, thus sending the steam over the door through pipe *e* and into pipes and coils *c*, from which the water of condensation enters the boiler A through pipe *h*; and to keep the water in the boiler at a certain level, and to dispose of the surplus thereof, the overflow-cock 7 is kept open sufficiently to accomplish 60 65 those ends.

Thus, as above described, by providing a supply-main in the cars for the reception of

steam from the locomotive and connecting therewith warming-coils on each side of the car, provided with proper drip-pipes, each car 70 of a train is adequately and constantly supplied with sufficient steam to keep the cars warm and comfortable while the locomotive is connected with the train and the steam-main and its connections are unobstructed. When, however, 75 the locomotive must for any cause leave the train or a part thereof standing on the road, or when one or more of the cars are switched off on a side track to await further use, it is requisite and necessary that there be auxiliary means 80 for warming or keeping the car or cars warm connected with each car and utilizing the same warming-pipes which, when the locomotive is connected with the cars, are supplied with steam 85 therefrom, and such is the purpose of the connection with the car and said system of heating-pipes of the boiler A, the operation of which and its connections is as follows:

As above described, the boiler has hot water constantly supplied to it while steam is 90 circulating in the pipes in the car, and is ready at all times to have a fire lighted under it, whereby steam is generated for the pipes in it. When it is known that a car is to be detached from a train which it is desired to 95 keep warm, the pipes *c* and *c'* and the boiler A are filled with live steam from the locomotive at such pressure as may be on pipe *b*, or as may be desired. The fire under the boiler is started and continued until the return of 100 the locomotive, and then it is extinguished in order that there may be no fire on the car while the train is in motion.

When a fire is lighted under the boiler, as above described, valves 6 and 4 are shut, provided only moderate warmth is required in the car, and the steam circulation from the boiler through pipe *i* into pipes *c* is confined to those heating-pipes, and the water of condensation therefrom is returned to the boiler through pipe *h*, and no considerable waste of water takes place; but what little there may be is replaced by drawing from reservoir K. If more heat be required in the car, the steam from the boiler may be allowed to pass through pipe *e*, and by opening valve 6 to circulate in pipe *b*, and thence through valve 5, valve 3 being shut, the condensation escaping through pipe *d* to the boiler. When connection is again made with the locomotive, the fire in the 110 boiler is extinguished and the various valves are arranged as before, to provide for the circulation of steam from pipe *b*, and to conduct the condensation from the heating-pipes, as 115 above described.

120 From the foregoing description of the construction and arrangement of the said car-heating devices it will be seen that the room usually occupied by stoves in a car can be utilized for seat-room, as all the heating-pipes 125 are so arranged as to be under or lower than the seats; that economy results from this manner of heating, since it costs less to produce the heating agent on a comparatively large

scale, as it is done by the locomotive, than to heat by many separate stoves or boilers distributed through the several cars of a train; that the steady supply of steam from the locomotive conduces to a regular and even temperature in the cars, whereby the passengers travel with much greater comfort, and all dust and dirt caused by stoves are avoided.

I am aware that it has been proposed to heat the cars of a train by hot water passing through one or more circuits of pipes extending the entire length of the train and passing through the fire-box of a locomotive; also, that steam and water pipes extending through a series of cars from one heater, with auxiliary heaters in each car, have been devised. It has also been proposed to heat the cars of a train by a main pipe from the locomotive extending throughout the train and radiators in each car connected therewith, but capable of being cut off from the main.

What I claim as my invention is—

1. The within-described improved means for warming railway-cars by steam taken from the locomotive, which consist of a main steam-pipe running through the car and adapted to be connected with the locomotive, a series of warming-pipes located above and connected with said main steam-pipe, cut-off valves in the connections, and suitable drip-pipes connected with said warming-pipes, combined and operating substantially as set forth.

2. The within-described means for warming railway-cars by steam taken from the locomotive, which consist of a main steam-pipe running through the car and adapted to be connected with the locomotive, two series of warming-pipes, substantially as described, one located on each side of the car and connected

with said main steam-pipe, cut-off valves between said series, and one or more drip-pipes connected with each series of said warming-pipes, combined and operating substantially as set forth.

3. The combination, in a railway-car, of a main steam-supply pipe adapted to be connected with the locomotive, and one or more series of warming-pipes arranged above and connected with said main pipe, a boiler having a heating device, substantially as described, attached thereto and suspended under the car, one or more drip-pipes leading from said series of warming-pipes into said boiler, a steam-pipe leading from said boiler and adapted to convey steam therefrom to one or more of said series of warming-pipes, and means, substantially as described, for controlling the flow of steam from said boiler through said warming-pipes, substantially as set forth.

4. The combination, in a railway-car, of the series of pipes *c'*, the drip-pipe *h*, the boiler *A*, having a suitable heating device attached thereto, the steam-pipe *i*, and valves in the connecting-pipes for controlling the flow of steam from the boiler through the pipes *c'*, substantially as set forth.

5. The combination, in a railway-car, of the series of pipes *c* and *c'*, the pipe *e*, the drip-pipe *h*, the boiler *A*, having a suitable heating device attached thereto, the steam-pipe *i*, and valves for controlling the flow of steam from the boiler through the pipes *c* and *c'*, substantially as set forth.

JAMES EMERSON.
